UNITED STATES PATENT OFFICE.

PATRICK D. KEARNEY, OF SOUTH BEND, INDIANA.

VEHICLE-AXLE.

SPECIFICATION forming part of Letters Patent No. 315,041, dated April 7, 1885.

Application filed February 2, 1885. (No model.)

To all whom it may concern:

Be it known that I, PATRICK D. KEARNEY, a citizen of the United States, residing at South Bend, in the county of St. Joseph and State 5 of Indiana, have invented certain new and useful Improvements in Trusses or Axle-Supports, of which the following is a specification, reference being had therein to the accompanying drawings.

10 This invention relates to improvements in trusses or axle-supports, and has for its object to provide wagons with a very strong support to the axles for a given weight of material. This object is attained by the devices shown in 15 the accompanying drawings, forming a part of this specification, in which—

Figure 1 is a view taken from the under side of an axle. Fig. 2 is a transverse section of an axle and truss, taken on the line xx of Fig. 20 1. Fig. 3 is an elevation of an axle and truss, taken from the rear.

The letter A indicates a truss, which is secured to the axle B by means of bolts E and clips D, or in any other convenient manner. 25 This truss is formed of thin metal, and consists, preferably, of a single piece of metal, approximating the shape of an inverted letter U. The part A is made flat, to receive the

bottom of the axle B, and has downwardly-turned flanges A', the lower edges of which, a, 30 have a cross-section approaching that of an oval, as this form adds considerably to the strength of the flanges A', while it adds but little to the weight.

The principle of my construction consists in 35 so placing the flanges A' that the strain comes upon the edge thereof instead of flatwise.

C are the hounds, which are secured to the axle B by the bolts E, which also aid in holding the truss in its place.

Having described my invention, what I desire to secure by Letters Patent and claim is—

An axle-truss composed of a single piece of thin metal bent so as to approximate the shape 45 of an inverted letter U, and having the lower cross-section of the flanges thereof nearly of oval shape, as described, and for the purposes set forth.

In testimony whereof I affix my signature in 50 presence of two witnesses.

PATRICK D. KEARNEY.
